APPARATUS FOR COLORING PAPER

Application filed December 9, 1929. Serial No. 412,732.

This invention relates in general to the manufacture of paper, and, more particularly, to the manufacture of colored paper, the invention including improvements in the process of and apparatus for coloring paper during the process of manufacture, though it will be understood that the apparatus may be employed for coloring paper after the same has been calendered.

10 This invention finds particular utility for the purpose of coloring parts of newspaper so as to make it possible to employ a color sheet for the outside page of certain editions of a daily newspaper and without coloring 15 the inside pages thereof.

While the invention is described and illustrated as particularly employed for coloring one side of, or a portion of one side of, a sheet or web of paper in the course of manufacture, it will be understood that the invention finds utility for analogous purposes and, therefore, is applicable to a wide field of utility.

The principal objects and advantages of 25 this invention reside in the provision, in the manufacture of paper, of the improved step of coloring the paper or a portion thereof during manufacture; the provision of a process of manufacturing paper and for 30 coloring the same prior to drying or calendering, that is, while the paper is still moist; the provision of an improved apparatus for carrying out the process of this invention; the provision of an improved 35 means for coloring one side or a portion of one side of a sheet of paper during course of manufacture, more particularly while the paper is being fed at a substantially uniform rate of speed during the coloring application; the provision of improved 40 apparatus of the character referred to which may be employed in conjunction with the regular paper-making machine, and which is adapted to receive and conduct the web 45 of moist paper and color the same immediately after it leaves the paper-making machine; the provision of coloring apparatus, including a coloring delivering member and a series of coloring distributing 50 members operating in conjunction with a

transfer member for depositing a film or coating of color on a moving web evenly and positively; and the provision of an improved apparatus of the character referred to, which is simple in construction, readily 55 adjustable, and which is positive in its operation.

This invention is also characterized by the provision of an improved arrangement of liquid coloring delivery and distributing 60 members in which these elements may be adjusted so as to regulate the quantity of coloring fluid delivered, and so as to insure a uniform unfailing supply when once set; the provision of a device of the character described in which a liquid coloring delivering roller is maintained in contact with a distributing roller acted upon by spreading rollers, which delivering roller is in contact with a coloring transfer roller which is arranged so as to contact with one surface of a moving web of material, and wherein the moving web and the said delivering and distributing rollers are synchronously operated 70 at a substantially uniform speed, together 75 with the improved feeding means for the web.

This invention further has as objects thereof the provision of improved supporting and adjusting means for the entire apparatus, that is, the coating apparatus, so as to permit of truing up the coloring transfer roller; the provision of an improved arrangement for longitudinally displacing the spreader rollers, the provision of an improved spreader for the film of coloring fluid; and the provision of an improved adjusting means therefor.

The foregoing and such other objects and advantages of this invention as may appear or be pointed out as this description proceeds are attained in the structural embodiment illustrated in the accompanying drawings, in which:

Figure 1 is a side elevational view of apparatus constructed in accordance with the present invention;

Figure 2 is an enlarged top plan, parts being broken away;

Figure 3 is an enlarged side elevational view;

Figure 4 is an enlarged sectional view taken on the line 4—4 of Figure 2 looking in the direction indicated by the arrows;

Figure 5 is an enlarged fragmentary plan elevational view illustrating the supply tank and roller arrangement;

Figure 6 is an enlarged fragmentary view 10 of the spreader adjusting means, and

Figure 7 is an enlarged fragmentary sectional view of a portion of the fluid supply tank and spreader means.

The method or process of this invention 15 resides particularly in the step of applying coloring material to one side of a sheet or web of paper in the course of its manufacture, and preferably after it leaves the paper-making machine but prior to its final drying or calendering. The application of color 20 may be carried out during the step of calendering. It is preferable that this application of coloring material be carried out prior to the drying of the paper, for the reason 25 that a more even distribution of coloring material over the surface to which it is applied may be attained, and, at the same time, attain a fixed color, for the reason that the moisture in the paper causes the coloring 30 material to be absorbed to a certain extent by one side of the web or paper. The step in the process of the manufacture of paper, that is, the application of color to one side of a portion of the web of paper, 35 may be carried out by the apparatus disclosed in the accompanying drawings.

By reference herein to newspaper work it 40 is pointed out that special editions of newspapers today have the outside pages of the edition pink or green or some other color to make the front page stand out. Previously to our invention all newspapers known to us having this feature merely employed a different colored paper from the 45 rest of the edition and this resulted in not only the outside front page being colored but the inside of this page and the inside and outside of the back page which it forms an integral part of. In this invention it is 50 possible to color the sheet so that only the front page contains the distinctive coloring.

Referring now more particularly to the drawings, and first to Figure 1, we have illustrated a series 5 of rollers arranged in 55 superposed spaced relation, over which the web 6 of paper, such as newspaper, is carried, these rollers being arranged in a pair of pedestals 7, only one of which appears in this figure. The web passes alternately over 60 the rollers 5 and is delivered on to a shaft 8 to form a roll 9, the shaft 8 being mounted in suitable bearings 10.

One of the series 5 of rollers, indicated at 11, has the web of paper passing thereover so 65 as to have one surface exposed toward the

apparatus of this invention, indicated in general at 12.

The apparatus 12 includes, among other parts to be presently described, a base portion 13 provided with the pairs of lugs 14 70 and 15 suitably apertured to receive rods 16 as a supporting means therefor, said rods being carried by brackets 17 mounted on the pedestals 7. Set screws 18, 18 pass through the apertured lugs 14 and 15 so as to fix the 75 base 13 at an initial position of adjustment toward or away from the pedestals 7.

On the base 13 we mount a carriage which includes the side walls 19 and 20 suitably spaced at fixed points by the provision of 80 transverse tie rods 21, 22 and 23. These tie rods are provided with reduced extremities, as indicated at 24, 24 in Figure 2, and pass through suitable apertures in the side walls 19 and 20, and cap screws 25, 25 in each instance engage washers 26, 26, said cap screws passing into the reduced extremities 85 of the tie rods, which fixes the side walls at the proper distance apart.

The bottom edges of the side walls 19 and 20, as best seen in Figures 3 and 4, rest upon the base 13, and said base is provided with marginal flanges 27 and 28, thus forming a run-way or slide for the carriage.

The carriage is susceptible of slight angular displacement in the run-way thus formed by allowing a small margin of space between the outer surfaces of the side walls 19 and 20 and the inner surfaces of the flanges 27 and 28 so as to insure the transfer roller making true, uniform contact with the exposed surfaces of the web passing over the roller 11. The flanges 27 and 28 are affixed to the edges of the base 13 by the provision of cap screws 29, 29.

In order to adjust the carriage to and from the roller 11 on the base 13 we provide bearing members 30 and 31 secured by bolts 32 to the outer end of the base 13, and screw rods 33 and 34 are revolvably mounted in said bearings 30 and 31 and have their threaded portions 35 engaging suitably threaded apertures in lugs 36 bolted, as at 37, on the side walls 19 and 20 of the carriage. Hand wheels 38 and 39 may be employed for imparting rotation to the adjusting screw rods 33 and 34 for moving the carriage to and from the roller 11 or for canting the carriage one way or the other so as to true up the transfer roller, which will be presently described.

The carriage serves to support a container or tank 40, in which a suitable coloring or other fluid is deposited, said tank having a bottom wall which is curved upwardly, as indicated at 41, to form a support for the spreader structure to be described later, and the side walls 42 of said tank may be suitably secured to the walls 19 and 20 of the carriage in such position that the tank is 125 130

disposed below the coloring fluid delivery roller 43. This roller 43 is preferably metallic, truly cylindrical, and is mounted on shaft 44 carried in suitable bearings in the side walls 19 and 20 of the carriage. The end faces of the roller 43 are substantially in contact with lateral flanges 45 and 46 formed on the top edges of the side walls 42 of the tank so that, as said roller rotates in the direction of the arrow rod in Figure 4, these flanges 45 and 46 will remove fluid from the ends of the roller.

The rear wall 47 of the tank is spaced from the adjacent surface of the roller 43, and a hinged cover 48 is provided for filling the tank when necessary. It will be observed from an inspection of Figures 4 and 5 that the rear edges of the flanges 45 and 46 and the front edge of the cover 48 are spaced from the adjacent surfaces of the roller 43, as indicated at 45a and 46a, so as to prevent the creation of pressure in the tank and thus result in undue agitation of the fluid contained therein. The coloring fluid delivery roller 43 picks up a quantity of the coloring fluid on its cylindrical face and, in order to produce a uniform film of coloring fluid on the cylindrical surface of the roller 43, we provide a spreader which does not actually contact with the surface of the roller, though it may be made to so contact, but which is spaced a slight distance away from the cylindrical surface and will thus maintain a film on this surface which is substantially uniform throughout.

The spreader referred to comprises, as best shown in Figures 4, 6, and 7, a supporting casting or frame 50 secured to the upwardly extending portion 41 of the bottom wall of the tank. This frame 50 serves to support an end closing wall member 51 which is secured by screws 52 thereto and extends toward the roller 43. Between the member 50 and the wall 51 there is provided the spreader 53 which is conveniently an elongated metallic strip of resilient character which is held rigidly at one end between the wall 51 and the member 50, its movement limited by said wall in one direction, but is free to move toward the cylindrical surfaces of the roller 43 by a mechanism which will now be described.

As it is sometimes desirable that the spreader be closer to the roller at some points than others, throughout its length, we provide a plurality of adjusting elements which include rocker arms 54, 54 mounted on a common shaft 55 carried in bearings 56 on the outer or upper surface of the end wall 51. As all of these rocker arms are substantially identical, a description of but one will suffice, reference for this purpose being best had to Figure 7 wherein the parts are shown enlarged. Under one end of the rocker arm 54 there is provided a pin 56

which is slidable in a suitable aperture provided beneath the rocker arm in the wall 51 so that when the rocker arm presses on the pin 56, that portion of the resilient spreader strip 53 adjacent thereto will be deflected toward the cylindrical surfaces of the roller 43. In order to produce this movement, there is provided a complementary rod 57 which is slidable in suitably aligned apertures formed beneath the opposite ends of the complementary rocker arm in the members 50 and 51. This rod extends below the bottom of the tank and may be provided with an enlarged threaded portion 58 and a knurled portion 59, the threaded portion operating in threaded engagement with a lug 60 affixed to the bottom of the tank. Upon rotation of the rod 57 it will be caused to move longitudinally and thus impart movement to one end of the rocker arm 54 which, in turn, at its other end displaces the adjacent portion of the spreader. There are a series of the rocker arms, as already pointed out, and thus a very accurate adjustment of the spreader at substantially any point throughout its length can be attained.

We provide a coloring fluid distributing roller 61 mounted in substantially the same plane as the roller 43 but spaced therefrom and carried by and rotatable with a shaft 62 mounted in suitable bearings in the side walls 19 and 20 of the carriage.

The distributing roller 61 receives coloring fluid from the delivery roller 43 by the provision of an idler roller 63. The roller 61 is formed of metallic material similar to the roller 43, but the roller 63 has its cylindrical surface at least, formed of rubber or similar yielding substance and is mounted in suitable angularly displaceable bearing members, 64, pivoted for such angular displacement at 65 on the side walls 19 and 20. Adjustment of the bearings 64 may be accomplished by manipulation of the pairs of set screws 66 operating in lugs 67 carried by the said side walls. This adjustment insures that the idler roller will uniformly contact with the adjacent surfaces of both of the rollers 43 and 61 and thus transfer the film of coloring fluid uniformly to the roller 61. The side walls 19 and 20 are recessed at their upper portions, as indicated at 68, so as to permit of the angular displacement of the bearings 64 and roller 63, as previously explained.

The roller 61 in turn contacts with a plurality of spreading rollers, three of which serve to carry out the function properly, and these are indicated at 69, these rollers being best seen from an inspection of Figure 4. The rollers 69 are made of the same general substances as the idler roller 63, that is, of rubber or other suitably resilient material, and are mounted as idling rollers, that

is, are not driven other than by frictional contact with the roller 61. These rollers 69 are mounted on suitable shafts 70, the outermost roller, indicated at 71, being 5 mounted on a suitable shaft 71a, and the three rollers 69 and 71 being longitudinally slidable on their axes while in contact with the roller 61 for further distributing the coloring fluid thereon. The side wall 19 is 10 provided with an opening 19a for accommodating the rollers 69 and 71 so that, as the rollers 69 are oscillated on their longitudinal axes, space will be provided for this purpose.

15 In order to impart oscillating movement to the rollers 69, we provide a bracket 75 secured by cap screws or bolts 76 on the side walls 19, said bracket extending downwardly and outwardly below the shafts 70 of the rollers 69. The shafts 70 are provided with collars 77 and 78 having each a circumferential groove. On the bracket 75 there is mounted a rocker arm 79 pivoted at 80 and having at each end a pin, these pins being indicated at 81 and 82 and lying in the grooves in the collars. The pins are provided with suitable small rollers so as to eliminate friction.

20 Oscillating movement is imparted to the collar 77 which, in turn, imparts similar movement in an opposite direction to the collar 78 and rocker arm 79 by the provision of a lever 83 fixedly secured to the longitudinal shaft 84 mounted in bearings 85 and 86 on the side wall 19. The lever 83 is provided with a pin having a roller 87 thereon entering the groove in the collar 77, and a similar lever 88 is mounted on the shaft 84 and is provided with a roller 89 entering 25 the groove on the collar 90 carried by the shaft 71a. It will be observed that upon oscillation of the shaft 84 the three rollers will be caused to slide in their respective bearings.

25 In order to impart oscillating movement to the shaft 84, a lever 91 extends upwardly from said shaft adjacent to the shaft 44 of the roller 43, and said lever is provided with a roller 92 entering a groove in a collar 93 carried by the shaft 44, the groove in the collar 93 being tortuous so as to form a cam 93, as indicated at 95 in Figure 2.

30 In order to impart simultaneous motion to the delivery roller 43 and the distributing roller 61, the shafts 44 and 62, respectively, of these rollers are extended and provided with sprocket wheels 94 and 95 connected by suitable roller 96.

35 The shaft 62 of the roller 61 may be extended at the opposite end and connected by a suitable means to a source of power, such as an electric motor, or the like, not shown.

40 In order to transfer the coloring fluid 63 thus distributed on the roller 61 to the paper

web, we provide a transfer roller 97 mounted on a shaft 98 carried in suitable bearings 99 projecting forwardly from the side walls 19 and 20, said roller 97 being formed of resilient material, such as rubber and the like, similar to the idler roller 63 and the oscillating distributing rollers 69 and 71. It will be observed that by an adjustment of the carriage, the pressure of the roller 97 on the paper web, and its uniform contact with said web, may be attained.

45 In the operation of the invention, fluid is picked up by the roller 43 and delivered to the idler roller 63 which conducts the fluid to the distributing roller 61. In order to insure an even distribution of the fluid on this roller 61, it is rotated in the same direction as the roller 43 and thus the film of coloring fluid is acted upon by the rollers 69 and 71, to be further distributed before 50 it reaches the transfer roller 97, whereupon it is conducted by this roller to the exposed surface of the paper web.

55 It will be understood that the rollers 43 and 61 are driven at such speed that the 50 lineal speed of the transfer roller 97 will be substantially the same as that of the web of paper 6.

60 As the web of paper is of greater width than the length of the transfer roller, only 55 a part of the exposed surface of the paper web is coated, usually of the width of a standard newspaper page, so that as the paper is later printed on and folded in the press, it will issue therefrom with only the 65 front page colored, the remainder of the sheet being uncolored.

65 A suitable cover may be provided for the 70 coating apparatus just described, including a cover for the carriage, but this has not 75 been shown. In order to prevent any such cover from coming in contact with the surfaces of the rollers 43 or 61, there are provided two bow-spring elements 68a and 69a secured at their ends by screws 69b on the 80 top edges of the side walls 19 and 20 and lying above the uppermost position of the idler roller 63 so as to support the cover above said rollers and out of contact therewith.

75 Having thus described our invention and 85 illustrated its use, what we claim as new and desire to secure by Letters Patent is:

80 1. In a device of the character described, in combination, means for conducting a web or film of material to be fed at a uniform rate of speed, a container for coloring fluid, and means operating synchronously with 85 said conducting means for applying a coloring material from said container to a portion of said web or film.

85 2. In a device of the character described, in combination, means for conducting a web or film of material to be fed at a uniform rate of speed, a container for coloring fluid, and 90

means operating synchronously with said conducting means for applying a coloring material from said container to a portion of one side of said web or film.

5 3. In a device of the character described, in combination, means for conducting a web or film of material to be fed at a uniform rate of speed, color applying apparatus including a container for a coloring fluid, said 10 conducting means including rolls arranged in superposed spaced relationship around whose surfaces said web is adapted to move, means for conveying a coloring fluid from said container to one side of the web including a roller submerged in the fluid in said container and a series of fluid conducting rollers extending from said submerged roller and contacting therewith at one end and at the other end with said web.

20 4. In a device of the character described, in combination, means for conducting a web or film of material to be fed at a uniform rate of speed, a container for a coloring fluid, said feeding means including rollers ar- 25 ranged in superposed spaced relationship around whose surfaces said web is adapted to move, means for conveying a coloring fluid from said container to one side of the web including a roller submerged in the 30 fluid in said container and a series of fluid conveying rollers extending from said sub- merged roller and contacting therewith at one end and at the other end with said web, and means for adjusting the pressure at said 35 points of contact.

5. In a device of the character described, in combination, a liquid feeding mechanism including a liquid container, a delivery roller operating in said container, a distribut- 40 ing roller in communication with said de- livery roller to receive liquid therefrom, spreading means cooperating with said distribut- 45 ing roller, and a transfer roller in contact with the latter.

45 6. In a device of the character described, in combination, a liquid feeding mechanism including a liquid container, a delivery roller operating in said container, a distribut- 50 ing roller in communication with said de- livery roller to receive liquid therefrom, means for driving said rollers at substan- 55 tially the same rate of speed, spreading means cooperating with said distributing roller, and a transfer roller in contact with the latter.

7. In a device of the character described, in combination, a liquid feeding mechanism including a liquid container, a delivery roller operating in said container, a distribut- 60 ing roller in communication with said de- livery roller to receive liquid therefrom, spreading means cooperating with said distribut- 65 ing roller, and a transfer roller in contact with the latter, and means for bodily moving said liquid feeding mechanism.

8. In a device of the character described, in combination, a liquid feeding mechanism including a liquid container, a delivery roller operating in said container, a distribut- 70 ing roller in communication with said de- livery roller to receive liquid therefrom, means for regulating the thickness of the liquid film on said delivery roller, spreading means cooperating with said distributing roller, and a transfer roller in contact with 75 the latter.

9. In a device of the character described, in combination, a liquid feeding mechanism including a liquid container, a delivery roller operating in said container, a distributing 80 roller in communication with said delivery roller to receive liquid therefrom, a plural- 85 ity of laterally displaceable spreading rollers coacting with said distributing roller, and a transfer roller in contact with the latter.

10. In a device of the character described, in combination, a liquid feeding mechanism including a liquid container, a delivery roller operating in said container, a distributing 90 roller in communication with said delivery roller to receive liquid therefrom, a plural- 95 ity of laterally displaceable spreading rollers coacting with said distributing roller, a transfer roller in contact with the latter, and means for displacing said spreading rollers, said means being operated by driving means for said delivering and distributing rollers.

11. In a device of the character described, in combination, means for conducting a web or film of material to be fed at a uniform rate of speed, color applying apparatus including a container for a coloring fluid, said conducting means including rollers arranged in superposed spaced relationship around 100 whose surfaces said web is adapted to move, means for conveying a coloring fluid from said container to one side of the web including a roller submerged in the fluid in said 105 container and a series of fluid conducting rollers extending from said submerged roller and contacting therewith at one end and at the other end with said web, and a spreader acting on the liquid carried by said roller for limiting the thickness of the film of such 110 liquid.

12. In a device of the character described, in combination, means for conducting a web or film of material to be fed at a uniform rate of speed, color applying apparatus including a container for a coloring fluid, said conducting means including rollers arranged in superposed spaced relationship around whose surfaces said web is adapted to move, means for conveying a coloring fluid from 120 said container to one side of the web including a roller submerged in the fluid in said container and a series of fluid conducting rollers extending from said submerged roller and contacting therewith at one end 125 130

and at the other end with said web, and a spreader acting on the liquid carried by said roller for limiting the thickness of the film of such liquid, and means for adjusting said spreader.

13. In a device of the character described, in combination, means for conducting a web or film of material to be fed at a uniform rate of speed, color applying apparatus including a container for a coloring fluid, said conducting means including rollers arranged in superposed spaced relationship around whose surfaces said web is adapted to move, means for conveying a coloring fluid from said container to one side of the web including a roller submerged in the fluid in said container and a series of fluid conducting rollers extending from said submerged roller and contacting therewith at one end and at the other end with said web, and a spreader acting on the liquid carried by said roller for limiting the thickness of the film of such liquid, and means for adjusting said spreader, said spreader comprising a flexible blade, and means for flexing said blade at a predetermined locality.

14. In combination, a tank for liquid to serve as a coating material, a delivery roller of metallic material having a portion thereof immersed in said tank, a distributing roller of metallic material mounted in substantially the same plane as said delivery roller but spaced therefrom and parallel thereto, and a non-metallic idler roller lying above and in contact with said delivery and distributing rollers for establishing communication therebetween.

15. In combination, a tank for liquid to serve as a coating material, a delivery roller of metallic material having a portion thereof immersed in said tank, a distributing roller of metallic material mounted in substantially the same plane as said delivery roller but spaced therefrom and parallel thereto, means adjacent to the peripheral surface of said delivery roller for limiting the thickness of the liquid film delivered thereby, and a non-metallic idler roller lying above and in contact with said delivery and distributing rollers for establishing communication therebetween.

16. In combination, a tank for liquid to serve as a coating material, a delivery roller of metallic material having a portion thereof immersed in said tank, a distributing roller of metallic material mounted in substantially the same plane as said delivery roller but spaced therefrom and parallel thereto, means mounted on said tank adjacent to the peripheral surface of said delivery roller for limiting the thickness of the liquid film delivered thereby, and a non-metallic idler roller lying above and in contact with said delivery and distributing rollers for establishing communication therebetween.

17. In combination, a tank for liquid to serve as a coating material, a delivery roller of metallic material having a portion thereof immersed in said tank, a distributing roller of metallic material mounted in substantially the same plane as said delivery roller but spaced therefrom and parallel thereto, means adjacent to the peripheral surface of said delivery roller for limiting the thickness of the liquid film delivered thereby, and a non-metallic idler roller lying above and in contact with said delivery and distributing rollers for establishing communication therebetween, said delivery roller rotating in a direction so that its surface delivering the liquid first approaches and passes said means and thence into contact with said idler roller.

18. In combination, a tank for liquid to serve as a coating material, a roller for delivering a film of such liquid from the tank mounted so as to be partly immersed in the contents thereof, said tank having end marginal flanges substantially radially disposed with respect to the roller and in contact with portions of the ends of the roller, the remaining portions of the roller being out of contact with and spaced from the walls of the tank.

19. In a device of the character described, in combination, means for conducting a web or film of material to be fed at a uniform rate of speed, a container for coloring fluid, and means operating synchronously with said conducting means for applying a coloring material from said container to a portion of said web or film, and means for bodily moving said container and color applying means relatively to said web.

20. In a device of the character described, in combination, means for conducting a web or film of material to be fed at a uniform rate of speed, color applying apparatus including a container for a coloring fluid, said conducting means including rollers arranged in superposed spaced relationship around whose surfaces said web is adapted to move, means for conveying a coloring fluid from said container to one side of the web including a roller submerged in the fluid in said container and a series of fluid conducting rollers extending from said submerged roller and contacting therewith at one end and at the other end with said web, and means for bodily moving said color applying apparatus relatively to said web.

21. In a device of the character described, in combination, means for conducting a web or film of material to be fed at a uniform rate of speed, color applying apparatus including a container for a coloring fluid, said conducting means including rollers arranged in superposed spaced relationship around whose surfaces said web is adapted to move, means for conveying a coloring fluid from

said container to one side of the web including a roller submerged in the fluid in said container and a series of fluid conducting rollers extending from said submerged roller 5 and contacting therewith at one end and at the other end with said web, and means for bodily moving said color applying apparatus relatively to said web, said last mentioned means permitting slight lateral and 10 angular bodily displacement as well for aligning the transfer means with said web.

22. In a device of the character described, a liquid delivering roller, a distributing roller in communication therewith, a transfer 15 roller contacting with said distributing roller for conducting a film of liquid therefrom to a moving web, a spreading roller in contact with said distributing roller, and means actuated by said delivering roller for moving 20 said spreading roller along its axis.

In testimony whereof, we have hereunto signed our names.

HERMAN BLACK.

WILLIAM HOLMES.

25 MAURICE ALBERT HESSE.
